arc becomes extinguished. To further insure the proper action of this style of arc regulating and forming device, and to produce a perfect arc lighting system, the independent automatic cut-out and regulator shown at Fig. 4 is employed. This device, which is entirely independent of the lamp, is designed to be placed in some convenient position to be of easy access; and it consists of a resistance, j , about equal to the resistance of the arc and the lead wire, one end of which is joined to the positive wire k of the main circuit and the other end to a contact-block, j' . Another contact-block, j'' , is connected to the negative wire k' of the main circuit, and this block is connected to the block j' , to close this shunt-circuit, by means of the bridge-piece l , pivoted to the end of the lever l' , said closing being caused by the spring l'' . To the other end of the lever l' is secured an armature, m , which is acted upon by the iron core of the magnet n . This magnet is wound with large wire, so as to have no perceptible resistance, and is included in the lead wire o , which conveys the positive current to the lamp, the return-wire o' from the lamp being joined to the contact-block j'' of the wire k' of the main circuit.

p represents a key or switch, by means of which the lamp-circuit may be opened or closed. When this key is moved back, as shown by the dotted lines, the bridge-piece l closes the circuit having the resistance j . If the lamp is in position ready to be used with the carbons in contact, and the key p be closed, the magnet n attracts the armature m and opens the shunt resistance, j , circuit, causing the whole current to flow through the lamp, the arc of which is then formed by reason of the portion of the current which flows through the magnet f in the derived circuit. As long as the lamp is working properly the magnet n keeps the resistance j out of circuit; but should the arc become extinguished the lever l' is instantly released, as the current then passing through n is not sufficient to counteract the spring l'' , and the bridge-piece l completes the shunt resistance, j , circuit. The carbons are allowed to close, as before described, which reduces the current in the magnet f , and also in resistance j , and charges the magnet n sufficiently to open the resistance j circuit. This action of the magnet n is retarded to allow the armature of the magnet f to fall and grip the rod e' , to be ready to form a new arc as soon as all the current is caused to pass through the lamp-circuit. This retardation of the action of the magnet n to open the bridge-piece l is accomplished by slotting the connecting-hole of l to lever l' , so that the lever l' has to be moved

a considerable distance before the bridge-piece l is raised. A dash-pot or other retarding device may be connected to the lever l' ; but such will not generally be necessary.

It will be observed that while this independent automatic cut-out and regulator is particularly adapted to be used in combination with the lamp above described, it may with advantage be used with other electric lamps.

What I claim, and desire to secure by Letters Patent, is—

1. In an electric lamp, in combination, an electro-magnet in a branch circuit around the arc-circuit, a rotating armature, a clamp device carried by the armature, and two adjustable stops adapted to open the clamp device when the armature is in its two extreme positions, substantially as and for the purpose set forth.

2. In combination, the carbon-holding rod e' , the hollow-core magnet f , having a toothed head, the armature g , also having toothed projections, and provided with a clamping device, and the supporting-rods $g' g' g'$, substantially as set forth.

3. An electro-magnet in which a prolongation of one of its poles is free to be acted upon by the other to be moved thereby, having the following elements in combination: upper pole, f^2 , base-pole, round end rods, $g' g' g'$, of iron, resting in recesses in the base-pole, and armature g , resting on the rods $g' g' g'$, substantially as set forth.

4. In combination, the clamp h , stops i and i' , carbon rod e' , armature g , hollow-core electro-magnet $f f' f^2$, and supporting-rods $g' g' g'$, substantially as set forth.

5. In combination, the clamp h , stops i and i' , carbon rod e' , armature g , hollow-core electro-magnet $f f' f^2$, supporting-rods $g' g' g'$, and spring i^2 , substantially as set forth.

6. In combination, the lower carbon rod supporting-bars $b b$, the globe c , and the hooks $c' c'$, pivoted to the bars $b b$, so as to hold the globe positively by catching under the flange around its opening, substantially as set forth.

7. The resistance j , contact-blocks $j' j''$, in combination with the main circuit $k k'$ and the spring-acting lever l' , with the bridge-piece l and the magnet n , included in the lamp-circuit $o o'$, substantially as set forth.

In testimony whereof I have hereunto set my hand, at New York, county and State of New York, this 6th day of October, A. D. 1882.

UNITED STATES PATENT OFFICE.

ALFRED SHEDLOCK, OF BROOKLYN, NEW YORK, ASSIGNOR, BY DIRECT AND MESNE ASSIGNMENTS, TO THE STAR ELECTRIC LIGHT AND POWER COMPANY OF THE UNITED STATES.

ELECTRIC-ARC LAMP.

SPECIFICATION forming part of Letters Patent No. 277,167, dated May 8, 1883.

Application filed October 7, 1882. (No model.)

To all whom it may concern:

Be it known that I, ALFRED SHEDLOCK, of Brooklyn, county of Kings, State of New York, have invented certain new and useful Improvements in Electric-Arc Lamps, of which the following is a specification.

This invention relates to that type of electric-arc lamps in which the lower carbon is stationary and the upper carbon fed by gravity to maintain the arc.

The invention embraces improvements in the lamp by which perfect control of the arc is had, and also an improved independent automatic cut-out and auxiliary regulator and key, arranged to be of easy access and located at a distance from the lamp.

The improvements in the lamp consist of a clamping device for holding the upper carbon rod, carried or controlled by the armature of an electro-magnet of high resistance relatively to the arc included in a shunt-circuit, the main lamp-circuit including nothing but the arc and carbon rods. To enable this derived electro-magnet to act to form the arc, and to control the downward movement of the upper carbon rod, the clamp is so constructed and actuated by the movement of the armature of the magnet as to release the rod when no current is passing through the magnet, and also when the current therein is at the maximum, which occurs when the resistance of the arc increases above the normal and when the arc becomes extinguished. With a normal arc the armature is so adjusted that the carbon-rod clamp carried or controlled thereby is floating between the stops or guides which operate it, so that a variation of the current in either direction causes the clamp to act to release the rod.

The independent automatic cut-out and regulator consists of an electro-magnet whose inducing conductor consists of a few convolutions of large wire forming part of the lamp-circuit, to the armature-lever of which are connected contact-points, which complete a shunt-circuit having a resistance about equal to the branch of the main circuit, including the arc of the lamp. The power of this magnet is such that the resistance shunt-circuit is open when the lamp-circuit resistance is normal; but as soon

as the lamp-circuit increases in resistance beyond the working resistance due to the extinction of the arc, &c., then the shunt is closed, and the current through the derived circuit in the lamp, increasing at the same time, opens the clamp and allows the carbon to come in contact. Then for a short interval of time the shunt resistance circuit is in multiple circuit with the carbons and the derived clamp-governing circuit. Consequently the current to the derived clamp-governing circuit is reduced, and the armature of its magnet allowed to recede before the large wire magnet of the automatic cut-out acts on its armature to open the resistance shunt-circuit, which, when done, throws all the current into the lamp-circuit. The arc is then instantly formed by the increase of current in the derived clamp-governing circuit, the resistance of the helix and number of convolutions around the core of the magnet being such that sufficient current flows therethrough when the carbons are in contact to cause the armature to raise the upper carbon rod. An ordinary key is arranged to cut out the lamp-circuit as desired, allowing the whole of the current to pass through the shunt-circuit, having a resistance equal to the lamp-circuit, so that under all circumstances the main-circuit resistance is constant, irrespective of the number of arcs burning. The construction of the lamp is such that the same is very compact, and little or no shadows are cast by the arc.

In the accompanying drawings, Figure 1, Sheet 1, is a central sectional elevation of the lamp. Fig. 2, Sheet 1, is a side elevation of the arc forming and controlling mechanism. Fig. 3, Sheet 1, is a plan view of the same; and Fig. 4, Sheet 2, shows a front view of the independent automatic cut-off and regulator, illustrating the connection of the same with the lamp. Fig. 5, Sheet 3, is an enlarged view of the upper part of the lamp with one of the frame-rods broken away, showing the clamping device about to be released when the armatures are in the extreme upper position. Fig. 6, Sheet 3, is a plan of the globe and supporting-rods, showing the rods cut through just above the globe.
